UNITED STATES PATENT OFFICE

2,603,119

AUTOMATIC AUXILIARY TUNING DEVICE

Ronald E. Dearth, Lima, Ohio

Application May 23, 1950, Serial No. 163,612

5 Claims. (Cl. 84—312)

1

The present invention relates to string anchoring, tensioning and tuning devices for stringed musical instruments and has more particular reference to an attachment for a guitar, particularly a so-called Hawaiian guitar.

It is a matter of common knowledge to those familiar with guitar constructions that string tuning devices are usually at the head end of the neck and customarily referred to as string attaching and tuning keys. However, other guitars have been offered wherein the tuning keys or devices are at the butt end of the guitar body and close to the bridge and tail piece. As a matter of fact, the art to which the invention relates reveals that guitar makers and users have offered for use the regular tuning keys at the customary head end of the fretted neck and optionally usable auxiliary tuning means at the opposite, that is, the butt end of the body. Such auxiliary means is helpful to guitarists when they desire to switch quickly from a condition in which the guitar is tuned up to A natural to other situations wherein the guitar may be tuned up, let us say, to E natural.

I have discovered the need for a quickly and easily shiftable auxiliary string tensioning and guitar tuning device wherein, through the medium of a readily available handle, the performer may quickly and collectively change the pitches of the second, third and fifth strings automatically whereby the guitar may be tuned up to A, the standard pattern, and quickly shifted from A to E and then on to C sharp and from C sharp back to E and then back to A. It follows that with a simple feasible and efficient automatic tuner, auxiliary in nature, the guitarist may have at his command facilities to enable him to have at his finger tips three distinct pattern tunings for a greater range of utility and playing.

As will be evident from the specification, drawings and claims, I have evolved and produced a guitar attachment in the form of an automatic auxiliary string tensioning and tuning attachment in which manufacturers, users and others will find their essential needs fully met, contained and readily available.

Other objects and advantages will become more readily apparent from the following description and the accompanying illustrative drawings.

In the accompanying sheet of drawings wherein like numerals are employed to designate like parts throughout the views:

Figure 1 is a perspective view showing the guitar body, a fragmentary portion of the neck

and fretted finger-board and showing, more particularly, the general construction and arrangement of string anchoring means including the improved auxiliary tuning device;

5 Figure 2 is a fragmentary plan view of the body, usual six strings, three regularly anchored and three attached to the auxiliary tuning device, the lid on the latter being removed;

10 Figure 3 is a section, with parts in elevation, taken on the plane of the horizontal line 3—3 of Figure 2, looking in the direction of the arrows;

Figure 4 is a similar section taken on the horizontal line 4—4 of Figure 2;

15 Figures 5 and 6 are views based on Figure 4 but showing the handle in two positions to which it is moved in addition to its normal A-natural position.

20 Referring now to the drawings by reference numerals and lead lines and with attention directed first to Figure 1, the numeral 8 designates a guitar body which may be said to be "conventional" in form. The neck 10 is secured as usual to the end of the body and is provided with 25 a fretted finger-board 12. Fixed string attaching or anchoring means 13 is shown on the top side of the body at the butt end of said body. This being an ordinary type guitar, preferably of a Hawaiian type, it is shown as having six 30 conventional vibratory strings. For convenience and with reference to Figure 2, three strings, those denoted by the numerals 14, 15 and 16 have their left-hand ends stationarily anchored on the block-like anchor 13. These three strings are commonly referred to by performers as the first, fourth and sixth strings. The remaining three strings are distinguished from the first-named strings and from each other by the numerals 17, 18 and 19, respectively. The first three strings 14, 15 and 16 are fixed in so far as tuning is concerned. The other three strings 35 17, 18 and 19, otherwise called the second, third and fifth strings are adjustable in relation to the first three strings for the stated automatic tuning operation. It is the last-named three strings 17, 18 and 19 which are those to be simultaneously acted upon and with their tensions regulated for making a quick switch from one tuned pattern, for example, the standard

40 A-pattern to two optionally usable other tuned patterns, namely, the E and C-sharp patterns, denoted by the legends in Figures 4, 5 and 6.

45 50 It will be understood that I am not especially concerned with the system of grouping or adapting the six strings, that is, with three strings fixed

at their left-hand ends and three strings adjustable. It is the construction of the attachment device, that is, the device which I call the auxiliary automatic tuning attachment 20 with which I am concerned.

The attachment takes the form of a substantially rectangular box 22 having bearings in its opposite end walls to accommodate the coacting end portions of an oscillatory rocker shaft 24. One projecting end of the rocker shaft is provided with a lateral handle 26 which is engageable, when in horizontal positions with either of the outstanding stop lugs 28 or 30 as the case may be. (See Figure 2.) This "rocker" shaft might also be perhaps identified as a cam shaft because it is the "cam functioning" step with which I am concerned. More specifically, one side or surface of the shaft on the interior of the box has a clearance notch 32 and the portion opposite to this provides a cam surface 34. On the intermediate portion and projecting from one side is a tappet or second cam element 36 and on the same side and spaced longitudinally is another tappet 38 and opposite to the tappet 38 is still another properly arranged tappet or cam 40. These several cam elements or tappets are adapted to cooperate in proper relationship with several complementary string tensioning levers identified by the numerals 41, 42 and 43, respectively. Specifically, each lever is the same in construction and the description of one will suffice for all. That is to say, each lever is adapted to fulcrum against a fulcruming rib 44 on the interior of the box. The central portion of the lever is apertured as at 45 (see Figure 3) and this provides a suitable tilting or hinge connection between the lever and a supporting screw 46 therefor which transversely spans the receptacle portion of the box. The upper end portion of the lever is arranged so that it will be in a path for wiping contact with the coacting cam means on the oscillatory shaft. The lower swingable end portion of the lever 41 has an aperture therein to accommodate the knotted end portion 47 of the string and the last-named aperture is in alignment with coacting holes 48 and 49 in the respective inner and outer vertical walls of the box. These several holes 48 and 49 including the hole in the lower end portion of the lever coact in allowing the string to be "threaded" therethrough. In other words, in putting a string on the guitar the leading end is threaded through the holes from left to right in Figure 3 and the non-knotted end (not shown) is, of course, attached in the usual way to the tuning keys on the head at the end of the fretted finger-board or neck (not shown). Each string tensioning lever unit also includes a stop screw. There are three of these and for convenience of identification they are referred to as 41a, 42a and 43a (see Figure 2). That is to say, they line up respectively with the levers 41, 42 and 43 in the numeral order disclosed. These stop screws 41a, 42a and 43a are more or less optional, "fine tuning" devices. That is to say, they are not absolutely essential but are preferable in the over-all assemblage of means shown and claimed. Or, to put it otherwise, by having an oscillatory rocker shaft in a box and having three pivotally mounted levers 41, 42 and 43 in the same box having their upper ends resting in camming relation with the tappets or cam elements on the shaft, it is obvious that this coaction between the shaft and levers alone would serve to rock the levers back and forth and to put the strings

under tension. However, it may be desirable to make some fine tuning adjustment in any one of the several levers and this is accomplished by making resort to the extra or fine tuning set screws 41a, 42a and 43a in an obvious manner. The bottom of the attachment box is secured to the top of the guitar by screws or the like as shown at 50 in Figure 3. The open top of the box is closed in by an appropriate lid or cover 51.

Briefly summarized, the invention has to do with three strings, 14, 15 and 16, fixedly anchored to the anchoring block 13 and three strings 17, 18 and 19 anchored on their respective tilttable levers 41, 42 and 43 in a box which appropriately houses the levers. The levers rest in camming contact with cam means on the oscillatory rocker or cam shaft 24. The latter is adjusted to any one of three positions (Figures 4, 5 and 6, respectively) for simultaneously and automatically tuning the several strings 17, 18 and 19 in relation to the relatively fixed strings 14, 15 and 16. With the handle 26 in the inward or forward horizontal position shown in Figure 4, all six of the strings are in which may be called the normal A-natural pattern which is the relationship they would have if the attachment herein shown were not present on the guitar. By shifting the handle from right to left so that it takes the perpendicular position shown in Figure 5, the cam shaft and several levers move to positions which serve to tension the several strings 17, 18 and 19 and these adjusted positions in relation to the positions of strings 14, 15 and 16 tend to provide what is known as the E-natural tuned pattern. By the same token, when the handle 26 is swung over from the perpendicular position of Figure 5 to that in the horizontal rearward position in Figure 6, a further adjustment of the several levers in conjunction with their attached strings establishes the C-sharp tuning pattern.

I shall not attempt to name all of the strings by their letter names or show their relationships by indicating the pitch of each in relation to "A" on the piano and their relationships when they are tensioned and tuned to the various stages in Figures 4, 5 and 6, for, as before stated, it is the structure of the attachment box 20 and the mechanism therein which constitutes the invention hereinafter claimed.

Although the instrument herein disclosed has six strings, it is to be understood that the number of strings could be from, let us say, four to eight, more or less.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A guitar string anchoring and automatic tuning attachment comprising a casing, a rocker shaft mounted horizontally for oscillation in said casing and provided with individual cams at longitudinally spaced points and provided at one end, exteriorly of the casing, with a handle, a plurality of flat plate members hingedly mounted within the confines of said casing in close proximity to said cams, said plate members constituting levers, the upper ends thereof being en-

gageable with their respective cams, the lower ends of said members being apertured, and coacting walls of said casing being apertured and the various apertures being in suitable alignment with each other to accommodate strings and to permit the same to be attached to said levers.

2. A guitar string anchoring and variable tuning attachment comprising a box-like casing having a flat bottom adapted to be fastened on a guitar and having front and rear walls joined at their respective outer ends by end walls, the lower end portion of said front wall being provided with a plurality of apertures through which individual strings are adapted to pass, a horizontal rib on the interior of said front wall, said rib constituting a fulcruming element, a horizontally disposed rocker shaft mounted for oscillation in said casing and provided with longitudinally spaced cams, a handle located exteriorly of one end of the casing and connected to the corresponding end of said rocker shaft, a plurality of flat plate members located in said casing between the rocker shaft and front wall of the casing, said plate members constituting individual levers and said levers being fulcrumed and adapted to rock on said fulcruming element, the upper end portions of the respective levers being cooperable with their respective cams and the lower ends of said levers be apertured and the apertures being in alignment with the coacting apertures in said front wall, and a removable lid for the open top of said casing.

3. The structure specified in claim 2 wherein

the rear wall of said casing is also provided with apertures, the latter being in alignment with the respective apertures in said front wall to facilitate the step of threading strings through the apertures in the rear wall, apertures in the lower ends of the levers and then through the apertures in the front wall.

5 4. The structure specified in claim 2 in conjunction with supporting screws piercing and 10 mounted in the front and rear walls and also piercing said rib, the levers being pivotally mounted on the respective supporting screws.

15 5. The structure specified in claim 4 and a plurality of individual selectively usable set screws mounted in the rear wall of said casing and aligned with an engageable with the upper end portions of said levers for checking the swinging movement of the levers in directions toward said rear wall.
